Des. 187,482
Patented Mar. 22, 1960

187,482

CLOCK

Jack Bergman, Pittsburgh, Pa.

Application March 20, 1958, Serial No. 50,116

Term of patent 7 years

(Cl. D42—7)

Fig. 1.

Fig. 3.

Fig. 2.

Fig. 4.

Fig. 5.

Fig. 1 is a front elevation of a clock, showing my new design;

Fig. 2 is a side elevation;

Fig. 3 is a top plan view;

Fig. 4 is a rear elevation; and

Fig. 5 is a vertical sectional view taken through the clock at right angles to the face of the clock.

I claim:

The ornamental design for a clock, as shown.
